UNITED STATES PATENT OFFICE.

GOTTHOLD L. LANGER, OF PORTLAND, OREGON, ASSIGNOR, BY DIRECT AND MESNE ASSIGNMENTS, TO STICKY-FRUIT PACKAGING MACHINE COMPANY, OF PORTLAND, OREGON, A CORPORATION OF OREGON.

PACKAGING-MACHINE.

1,389,669.

Specification of Letters Patent.

Patented Sept. 6, 1921.

Application filed September 12, 1916. Serial No. 119,682.

To all whom it may concern:

Be it known that I, GOTTHOLD L. LANGER, a citizen of the United States, residing in the city of Portland, county of Multnomah, 5 and State of Oregon, have invented certain new and useful Improvements in Packaging Machines, of which the following is a specification.

My invention relates to packaging machines, and more particularly to machines of the character shown and described in my pending application, filed January 5, 1916, Serial Number 70,461, and which machines are adapted to automatically weigh a pre- 10 determined amount of matter; to wrap the same, and to discharge the wrapped package into an open box, or carton, adapted to receive the same.

Among the salient objects of the present 20 invention are,—to provide in a machine of the character referred to improved mechanism for weighing a predetermined amount of the matter to be wrapped and for discharging the same into the wrapping mechanism; to provide in combination therewith an improved and simplified receiving and wrapping mechanism, comprising a revolute wheel-like structure provided with a series of receiving wrapping pockets into 30 which wrapping paper and the matter to be wrapped are delivered, with successively positioned folding members to which said wheel carries said wrapping paper, and said matter, during its revolution, whereby the 35 paper is folded about the matter as it is moved adjacent said several folding members, thus eliminating the necessity for a complete set of folding members for each receiving pocket; to provide in a machine of 40 the character referred to, improved means for compressing the wrapped matter and for delivering it to an open box, or carton, and, in general, to provide a simple and practical automatic weighing and packaging machine of the character referred to.

In order that others may understand my invention, I have illustrated one practical embodiment thereof in the accompanying sheet of drawings, in which,—

50 Figure 1 is a side elevation of a machine embodying my invention;

Fig. 2 is a top plan view thereof;

Fig. 3 is an end view thereof;

Fig. 4 is a side elevation thereof from the opposite side to that shown in Fig. 1;

55

Fig. 5 is a vertical sectional view of the machine taken on line 5—5 of Figs. 2 and 3;

Fig. 6 is a fragmentary end view of that part of the mechanism shown at the left-hand upper side of Fig. 5;

60

Fig. 7 is a transverse vertical sectional view through the wheel having the wrapping pockets, taken on line 7—7 of Fig. 1;

65

Figs. 8, 9 and 10 are enlarged detail views, partly in section, showing a clutch mechanism for intermittently starting and stopping the machine;

Figs. 11, 12, 13, 14 and 15 are perspective views showing the successive steps in the wrapping operation from the time the wrapping paper and the matter to be wrapped are deposited in a wrapping pocket up to the time the completely wrapped matter is discharged from the machine into a carton.

70

Fig. 16 is a fragmentary top plan view 75 looking down on the line 16—16, of Fig. 5;

Fig. 17 shows an edge and outside face view of one of the bottom end folding wings; and

Fig. 18 shows side and edge views of a 80 detail.

Referring now more in detail to the drawings, my invention as here illustrated comprises a base 1, and three upright frame members 2, 3 and 4. Rotatably mounted between the frame members 3 and 4, upon an axle 5, is a wheel-like structure 6, having around its periphery a series of receiving wrapping pockets 6^a, 6^b, 6^c, 6^d, 6^e, 6^f, 6^g and 6^h, there being eight of these pockets in the present construction, each open at its ends and at its outer side, said wheel structure being keyed to the shaft 5, as at 7, as is also a large driving gear 8, just inside of the frame member 3, said wheel structure 6, being turned intermittently an eighth of a revolution by means of said gear 8. Referring to Fig. 5, which shows a vertical sectional view, it will be seen that said wheel structure turns within a surrounding band-like inclosure 9, made as a part of the frame structure, and forms a closure for the outer open sides of the wrapping pockets, as said wheel structure with said pockets are revolved therein; said inclosure, however, being open at its upper side, as at 10, at which

85

100

105

point each of the wrapping pockets of the wheel structure 6, stops to receive a quantity of the matter to be wrapped, as clearly illustrated in Fig. 5.

5 The machine is power driven, as by means of a pulley 11, mounted on a shaft 12, shown in section in Fig. 1, in which figure, and also in Fig. 2, said driving pulley is omitted. Said shaft 12, has a bearing in the frame member 2, and also in frame member 3, as will be clear from Figs. 2 and 3, and is provided immediately inside of frame member 2, with a loose pinion 13, having clutch teeth 14, on its inner face, adapted to have intermittent driving engagement with a clutch 15, for throwing the main part of the machine into and out of driving connection with the shaft 12, and the pulley 11, said clutch being shown in detail in Figs. 8, 9 20 and 10, and hereinafter more particularly described. A shaft 16, is mounted through the upright frame members 2, 3 and 4, as clearly seen in Fig. 3, said shaft being provided on its end outside of frame member 2, 25 with a slide gear 17, and on the inside of said frame member 2, with a gear 18, in mesh with the pinion 13, seen in Fig. 2. Said shaft 16, is also provided with slide gears 19 and 20, and at its opposite end, 30 outside the frame member 4, with a double slide gear, the parts of which are designated, respectively, 21 and 22, which parts are bolted together so as to bring their toothed portions and their smoothed portions in 35 proper relative positions for operating gears hereinafter referred to. A third shaft 23, is mounted through the frame members 2 and 3, directly underneath the shaft 12. On the outer end of this shaft, is a gear 24, having two sliding, or locking faces 24^a and 24^b, said gear 24, being adapted to be intermittently turned and locked by the gear 17, which has a short series of teeth, as at 17^a, 40 corresponding in number to the number of teeth on the opposite sides of the locking faces 24^a and 24^b, of the gear 24, whereby as said gear 17, revolves, it gives gear 24, a half turn with each complete revolution it makes. Mounted on the inner end of the said shaft 45 23, inside the frame member 3, is a gear, or pinion 25, which is shown in dotted lines in Fig. 2, and which pinion is directly behind the gear 23, shown in Fig. 1, and in mesh with the large gear 8, on the shaft 5, and by means of which the wheel structure 6, is driven.

I will now describe a clutch mechanism, shown in Figs. 8, 9 and 10, and by means of which the folding mechanisms and the 60 principal operating parts of the machine are intermittently thrown into and out of driving connection with the main driving shaft 12, on which the pulley 11, is mounted. As hereinbefore stated, the pinion 13, with 65 the clutch teeth 14, is loosely mounted on

said shaft 12. Also mounted on said shaft 12, is a companion clutch member, or sleeve, 26, having clutch teeth 27, adapted to be moved into and out of mesh with the clutch teeth 14, on the pinion 13, said clutch sleeve 70 26, being slidably secured to the shaft 12, by means of a feather 28, and normally moved into driving engagement with the pinion 13, by means of a spring 29, on said shaft 12, as clearly indicated in Figs. 2, 9 75 and 10. The clutch sleeve 26, is supported in a bearing member 30, said bearing member being held in place on said sleeve 26, by means of a nut 31, threaded on to said bearing sleeve 26, as clearly indicated in 80 Fig. 10. Said bearing member 30, is provided at its lower side with a guide sleeve 32, slidably mounted upon a shaft 33, having bearings in the frame members 2 and 3. Mounted upon the opposite side of the bearing member 30, is a plunger-like member 34, normally held in extended position by means of a spring 35, within the plunger casing 36, formed as a part of the bearing member 30, 85 as will be clear from Fig. 10. Said plunger 34, is provided with a notch 37, in one side, within which is adapted to seat a trip lever 38, which is normally drawn toward said plunger by means of a coiled spring 39, attached at its opposite end to a fixed pin 40, 90 set in the nut 31. The plunger 34, is provided with a rounded corner, as at 34^a, and is adapted to be engaged by a fixed cam block 41, mounted upon the inner face of the gear 18, whereby as said cam block 41, engages 100 said plunger 34, it forces said plunger, together with said bearing member 30, and the clutch sleeve 26, away from the clutch pinion 13, Fig. 9, thus disengaging the clutch teeth 27, of the clutch sleeve 26, from the 105 clutch teeth 14, on the inner face of the pinion 13. Inasmuch as the clutch sleeve 26, is slidably secured to the shaft 12, by means of the feather 28, it will be evident that when said parts are moved away from 110 the pinion 13, and out of mesh with the clutch teeth 14, as above stated, said pinion 13, and the large gear 18, will stand idle, the shaft 12, turning within said pinion 13, and the clutch sleeve 26, turning within the bearing member 30. The plunger 34, in the meantime, will rest upon the cam block 41, 115 on the large gear 18, in its stopped position, thus holding the clutch sleeve 26, and the clutch teeth 27, thereof, out of driving engagement with the clutch teeth 14, on said pinion 13. Therefore, when the trip lever 38, is moved outwardly, in a manner hereinafter described, out of the notch 37, in the plunger 34, it allows the bearing member 30, 120 and the clutch sleeve 26, to be moved inwardly into driving engagement with the clutch teeth 14, by means of the spring 29, whereupon said pinion 13, being again locked to the shaft 12, drives the large gear 125 130

18, moving the cam block on its inner face from under the plunger 34. Said plunger 34, is again thrust outwardly in its normal position by its spring 35, and the machine 5 continues to run until the gear 18, has made one complete revolution and the main cam block 41, thereon has again engaged said plunger 34, and again moved the bearing member 30, and the clutch 26, out of driving 10 engagement with the clutch teeth 14, of the pinion 13.

Thus it will be seen that the constantly driven shaft 12, is intermittently, by means of this clutch mechanism just described, 15 thrown into and out of driving engagement with the principal operating mechanism of the machine, said connection being from the clutch pinion 13, to the gear 18, on the shaft 16, on which shaft is also mounted the gears 20 17, 19, 20, 21 and 22, the shaft 23, being intermittently driven by its pinion 24, which is intermittently driven by the lock gear 17, from which shaft 23, the large gear 8, is driven through the pinion 25, thus intermittently turning the wheel structure 6, forwardly, step by step.

I will next describe the weighing mechanism by means of which the matter to be wrapped is weighed out in predetermined 30 amounts, together with the means for feeding this matter to the weighing mechanism, and also the means for feeding the wrapping paper into position to receive said matter from the weighing mechanism.

35 As my machine is especially designed for weighing and wrapping raisins, I have shown mechanism for separating the raisins as they are fed into the weighing mechanism. This mechanism is shown in Figs. 40 4, 5 and 6. The raisins are fed from any suitable hopper, or container, through a series of revolving separating fingered members 42—42, all driven together by means of a pulley 43, and connected to each other 45 by means of sprocket wheels 44—44, over which runs a sprocket chain 45. From the fingered members 42, the raisins are fed through on to a traveling belt 46, running over suitable rollers 47 and 48, supported at 50 one end upon a standard 49, upon the machine proper, and at its other end upon an independent standard 50, as clearly illustrated. Said belt 46, is driven by means of a sprocket chain 51, and a sprocket wheel 52, upon the outer end of the shaft on which the roller 47, is mounted. As the raisins are carried forwardly on the top lap of the belt 46, in the direction indicated by the arrow, Fig. 5, between the side pieces 53, 55 they are discharged as at 54, into the weighing box, or container, 55. Said weighing box 55, is pivotally supported between the outer ends of two arms 56—56, secured to a shaft 57. Mounted upon said 60 shaft 57, is a short arm 58, having a pivoted

short trip finger 59, adapted to underlie the weighted balance lever 60, pivotally mounted at its opposite end at 61, upon a shaft 62, and provided with an adjustable weight 63, adapted to be secured in place on said lever 70 60, by means of a thumb screw 64. The trip finger 59, pivoted to the short arm 58, is capable of being turned upwardly on its pivot, but can not be turned downwardly on said pivot. Therefore, as the raisins fill 75 the weighing box 55, and said box descends under its weight, the short arm 58, and its trip finger 59, move upwardly together, lifting the weighted lever 60, thus allowing the weighing box 55, to descend. Also secured to the shaft 57, intermediate its ends, is a rod 65, on which is a suitable balance weight 65^a, adapted for balancing the weighing box 55, and its mechanism when the same is empty. Secured to the opposite sides of 80 the weighing box 55, are ears 66—66, to which are pivotally attached at their upper ends operating arms 67—67, said operating arms being attached at their lower ends to slide bottom pieces 68—68, slidably mounted 85 in guide frames 69—69, carried by said weighing box 55, near its bottom, which bottom pieces are adapted to be moved into and out of said weighing box to receive, support and discharge the contents of said 90 weighing box.

Referring to Figs. 1 and 2, there is shown mounted on the side of the weighing box 55, a rocker lever 70, having a cam finger 71, adapted when said weighing box descends 100 to engage a cam block 72, mounted upon the top of the frame member 3, said rocker lever 70, being connected at its opposite ends by means of links 73—73, with the arms 67—67, whereupon as said weighing box 55, descends and said cam finger 71, engages the cam block 72, said rocker arm 70, is rocked, so as to move the levers 67—67, outwardly and away from the box 55, thus operating to open the bottom pieces 68—68, to allow the contents to drop out on to the wrapping paper, above the wrapping pocket, ready to receive the same, in a manner hereinafter described. The arms 67—67, and the bottom pieces 68—68, are drawn inwardly to close the bottom of said box, by means of a coiled spring 74, secured at its opposite ends to short arms 75—75, connected at their upper ends, as at 76—76, to the pivot shafts on which the arms 67—67, are mounted. Also mounted on one side of the box 55, is a bearing ring 77, adapted to move down between upstanding guide fingers 78, on a base 79, secured to the top of the frame 4. This prevents the box from tipping as it moves downwardly with its load.

A shut-off gate 80, is pivotally mounted, as at 81, between the side members 53, of the mechanism for feeding the raisins into 130

the box 55, said shut-off gate being operated by means of a bell crank 82, one arm of which is connected with a spring 83, for normally moving said gate open, in the position shown in full lines in Figs. 4 and 5. An operating link 84, is connected to the other arm of the bell crank 82, and swings freely along the side of the weighing box 55, where it is provided with a pin 85, adapted to be engaged by the box supporting arm 56, as it descends, thus operating to close the shut-off gate 80, and prevent the further feeding of raisins therethrough until the weighing box is again lifted and the gate opened by means of its spring 83.

Mounted across the top of the machine, directly above shaft 57, is a shaft 86, in the middle of which is mounted a sleeve 87, projecting from which is a yoke-like member 88, shown in top plan view in Fig. 2, and in section in Fig. 5. Said yoke-like member projects immediately above the arm 58, and is adapted when turned downwardly to engage said short arm 58, and to rock the shaft 57, for the purpose of raising the weighing box 55, after it has discharged its load. Mounted on one of the outer ends of said shaft 86, is a crank arm 89, having connected therewith the upper end of a pitman rod 90, the lower end of which is connected with a crank disk 91, on the inner face of which is a gear 92, seen in Figs. 1, 2 and 3, which gear is in mesh with the large gear 20, on the shaft 16.

Also mounted across the top of the frame members 3 and 4, and directly under the shaft 57, is a shaft 93, having mounted in its middle portion an arm 94, and on its end a crank arm 95, connected with which is a pitman 96, clearly shown in Fig. 1, the lower end of which pitman is connected with an arm 97, on a shaft 98, mounted between the upright frame members 2 and 3, and provided near the frame member 2, with a downwardly depending operating arm 99, adapted to engage and operate the trip lever 38, of the clutch mechanism, whereby to trip the clutch and allow it to be thrown into operating position, as hereinbefore described. Mounted on the shaft 57, between the arms 56—56, which carry the weighing box 55, is an operating arm 100, shown in dotted lines in Figs. 1 and 5, and in plan in Fig. 2. This arm is directly above the arm 94, on the shaft 93, whereby as weighing box 55, descends with its load the arm 100, is rocked downwardly with it until it engages the arm 94, thus rocking shaft 93, and through the parts 95, 96 and 97, also rocking shaft 98, so as to move the downwardly projecting arm 99, thereon, into engagement with the trip lever 38, for tripping the clutch, as above referred to, thus starting the machine as the matter to be

wrapped is discharged from the weighing box.

I will next describe the mechanism for supporting and feeding the wrapping paper into the machine, and for cutting it off in proper lengths for each package. Supporting brackets, as 101—101, are mounted on the frame members, as clearly shown in Figs. 1 and 5, between which a roll of wrapping paper 102, indicated in dotted lines, is supported. From the roll 102, the paper is fed under a roller 103, mounted between the frame members 3 and 4, thence forwardly between an upper roller 104, and a lower roller 105, the latter of which is provided with soft feeding rings 106, said feed rollers 104 and 105, being mounted upon shafts 107 and 108, respectively, on the outer ends of which are meshing gears 109 and 110, seen in Fig. 1. Mounted upon the opposite end of shaft 108, is a gear 111, having a smoothed locking face 112, shown in locked engagement with the inner gear 21, as seen in Figs. 3 and 4, the gear 21, being directly behind the gear 22, as shown in Fig. 4, some of the teeth of gear 21, being seen projecting from behind the gear 22, at the left-hand side thereof. Thus as shaft 16, is revolved, the gear 21, intermittently turns the gear 111, the shaft 108, and the feed rollers 104 and 105, feeding a quantity of the wrapping paper forwardly directly under the weighing box 55, and above the opening 10, in the wheel structure casing, as clearly shown in Fig. 5, said paper being indicated in position by a dotted line running from the roll 102, under the roll 103.

A knife 113, is pivotally mounted, as at 114, and is adapted to be closed down across the paper at the point 115, Fig. 5, thus cutting off a portion of the paper resting under the weighing box 55. Said knife, at its hinged end, has a short projecting arm 116, to which is connected an operating pitman 117, the lower end of which is connected to the end of a rocker arm 118, shown in dotted lines in Fig. 1, and seen in top edge view in Fig. 2, said arm projecting adjacent the inner face of the large gear 19, on which is mounted a trip roller 119, adapted with each revolution to engage said trip lever 118, and through the connections just described intermittently operate the knife 113, which shears the paper. The piece of wrapping paper thus cut, rests directly underneath the weighing box 55, so that as said weighing box receives a pre-determined amount of raisins, or other matter to be wrapped, and moves downwardly and discharges its contents, in the manner hereinbefore described, said contents causes the wrapping paper to sink through the opening 10, in the frame and into the uppermost pocket 6^a, in the wheel structure 6, as will

- be clear from Fig. 5. Referring to Fig. 7, it will be noted that there are two inclined side walls 120—120, depending from the under side of the top plate 121. These serve 5 to hold the opposite sides of the paper in an upwardly inclined position as it sinks with its weight into pocket 6^a, thus preventing the raisins from running out, the wrapping paper, as it sinks into the pocket 6^a, assuming the form shown in Fig. 11. At this 10 stage of the proceedings, the large gear 22, Fig. 4, which has been up to this point in locked sliding engagement with a small gear 122, turns said gear 122, which is provided 15 on its outer face with a crank disk 123, having thereon a crank pin 124, to which is connected a pitman 125, the opposite end of which is connected, at 126, with a segmental lever 127, pivotally mounted at its 20 lower end, as at 128, in the side member 4, and at its upper end provided with a segmental arc 127^a, having the two gear-locking surfaces 129 and 130, and the teeth 131. Pivotally mounted at the opposite sides of 25 the opening 10, in the top of the wheel structure casing, are two folding wings 132 and 133, shown in section in Fig. 5, and in dotted lines in Fig. 4. The shafts on which said folding wings are mounted, are provided 30 at their outer ends with lock gears 134 and 135, adapted to have operating and holding engagements with the segmental arc 127^a, so that as said segment lever 127, is moved, first to the right, it causes the folding 35 wing 132, to be folded over in the direction indicated by the arrow, Fig. 4, which folds one side of the paper down on to the contents in the pocket 6^a, and as said segmental lever 127, moves back to its middle 40 position, said folding wing is returned to its normal position, shown in dotted lines, and the continued movement of the segment lever 127, to the left operates to move the folding wing 133, thus folding the opposite 45 side of the paper down flatwise on to the contents, the package now assuming the form shown in Fig. 12. The folding wings 132 and 133, are successively moved, in the order mentioned, to fold first one side of the 50 paper and then the other side, the gear 122, having a locked sliding engagement with the gear 22, with the parts in the position shown in full lines, Fig. 4, until the next 55 pocket in the wheel structure has been moved up into receiving position, and the operation just described is repeated. As the folding wing 133, raises, the wheel structure 60 6^a, is given a one-eighth turn in the direction indicated by the arrow, Fig. 5, this being accomplished by the engagement of the pinion 25, with the large gear 8, which is mounted on the same shaft 5, with said wheel structure. The pinion 25, as before described, is mounted on the shaft 23, on which is also mounted the lock pinion 65 24, which turns said shaft 23, a half turn with each full revolution with said gear 17, as hereinbefore described.
- With the top sides of the wrapping paper folded over in the manner shown in Fig. 12, 70 the wheel structure 6, turns an eighth of a turn, in the direction indicated by the arrow, Fig. 5, bringing said partially wrapped package into a position between two end-folding wings 136—136, which are hingedly 75 mounted in the frame structure, as at 137—137, and in positions at the opposite ends of the wrapping pockets in the wheel structure 6, as said pockets are moved intermittently and successively between said bottom folding wings 136—136. Said bottom end-folding wings are operated by means of links, as 80 138, each being connected at one end, by means of a knuckle 139, to a short arm 140, mounted on the sleeve portion of each of 85 said wings, each of said links, 138, being connected at its upper end with a short crank arm 141, mounted on a shaft 142, supported in bearing brackets 143—143, mounted upon the frame, or closure, for the wheel 90 structure, as clearly shown in Fig. 5. Mounted upon the middle of said shaft 142, is a crank arm 144, connected with which is a link 145, provided on its opposite sides with a pair of rollers 146—146, said link 145, being connected at its lower end with the upper portion of a bell crank 147, shown in detail in Fig. 18, the lower part of said bell crank 147, being connected by means of a link 148, with a crank arm 149, the outer 95 end 150, of said crank arm being connected to a spring 151, and anchored at its lower end to the base 1, of said machine, as at 152. Mounted on the shaft 16, for engagement with the rollers 146—146, mounted on opposite sides of the link 145, is a double cam member 153, adapted to engage said roller as it revolves in the direction indicated by the arrow, Fig. 5, and to force said link 145, inwardly, thereby rocking the shaft 142, and 100 through the arms 141—141, and the links 138—138, closing the folding wings 136—136, at the opposite ends of the pocket inwardly, which folding wings fold the ends of the wrapping paper inwardly from the positions 105 shown in Fig. 12, to that shown in Fig. 13. The movement of said link 145, by the cam 153, also rocks the bell crank 147, and through the link 148, the arm 149, which operates to partially turn the beveled gears 154—154, mounted upon shaft 155, upon which the bell crank 147, is mounted, and also the gears 156—156, mounted upon the shaft 157, upon which the arm 149, is mounted. The gears 154—154, are in mesh 110 with beveled gears 158—158, through which are slidably mounted two shafts 159—159, which shafts 159 are feathered to their gears 115 120 125

158—158, and are provided on their inner ends with folding fingers 160—160, shown in dotted lines in Figs. 3 and 5. The gears 156—156, mesh with the gears 161—161, mounted on shafts 162—162, similar to the shafts 159, which shafts 162—162, are feathered to their gears 161, whereby to slide therethrough, and are provided on their inner ends with folding fingers 163—163, shown in dotted lines in Figs. 3 and 5, which fingers are similar to the fingers 160, and all four of which are simultaneously operated to fold the sides of the ends of the package inwardly, as shown in Fig. 14. Said fingers, however, normally rest in sockets, as 164—164, formed in the side of the casing, as shown in section in Fig. 5, in order to give clearance for the intermittent partial revolutions of the wheel structure 6, which brings one of the package pockets into position so that these fingers 160 and 163, can operate upon the opposite ends of the package, in the manner just described, leaving the package in the form shown in Fig. 14. In order to simultaneously and intermittently move said shafts 159 and 162, inwardly through the gears 158 and 161, so as to move said folding fingers 160 and 163, inwardly, into positions opposite the opposite ends of the package pocket 6^c, as indicated in dotted lines in Figs. 3 and 5, I provide connecting bars 165—165, connecting the shafts 159 with the shafts 162. Pivotaly connected at their lower ends to the middles of said bars 165—165, are two forks 166—166, pivotaly mounted near their upper ends upon a short shaft 167, having its bearings in the opposite frame members 3 and 4, each of said forks being provided at its upper end with two short arms 168—168, between which is mounted a roller 169, said rollers being adapted to engage cams 170—170, mounted upon the shaft 16, just inside the frame members 3 and 4, as clearly shown in Fig. 3, and one of which is also seen on shaft 16, in Fig. 5, this side of the double cam 153. Thus it will be seen that as said shaft 16, is intermittently revolved, in the manner hereinafter described, it operates through the double cam 153, to operate the folding wings 136—136, at the ends of pocket 6^b, in the wheel structure 6, and also the folding fingers 160 and 163, at the ends of pocket 6^c, folding the end of the package in pocket 6^b, from the position shown in Fig. 12, to the position shown in Fig. 13, and simultaneously folding the sides of the ends of the next package in advance, in pocket 6^c, from the condition shown in Fig. 13, to the condition shown in Fig. 14. Just preceding the folding of the sides of the ends, however, at pocket 6^c, the cams 170—170, rock the forks 166—166, so as to thrust the shafts 159 and 162 inwardly, so that when the double cam 153, moves the link 145, said

folding fingers can be operated in the manner just described.

Formed as a part of the sleeve on which the crank arm 149, is formed, is a gear segment 171, which is operated with the movement of the arm 149, to which is connected the operating link 148. Mounted between the frame members 3 and 4, is a shaft 172, provided in its middle with a gear 173, adapted to be intermittently operated by the gear segment 171. Mounted upon the opposite ends of the shaft 172, are beveled gears 174—174, which mesh with beveled gears 175—175, upon the upper ends of shaft 176, Fig. 5, which operate folding wings 177—177, shown in Figs. 3 and 5, these folding wings being so positioned that when a pocket of the wheel structure reaches that point, as 6^d, the package is in the form shown in Fig. 14, whereupon the folding wings 177, at the opposite ends of the pocket 6^d, Fig. 5, fold the top folds of the package into the positions shown in Fig. 15. Thus the wrapping paper is folded about the matter being wrapped, step by step, as shown in Figs. 12, 13, 14 and 15, as the package is successively advanced through the positions indicated by the pockets 6^a, 6^b, 6^c and 6^d, Fig. 5. With the next operation of the machine the folded package is moved to the position of pocket 6^e. It will be understood, of course, that there is a package in each of the pockets 6^a, 6^b, 6^c, 6^d and 6^e, being operated upon, simultaneously, the folding wings 132 and 133, folding the wrapping paper over the package into the position shown in Fig. 12, immediately preceding the partial rotation of the wheel structure 6, and during the next stop the bottom end folders 136, the side end folders 160—163 and the top end folders 177, are all simultaneously operated through the action of the double cam 153. In order to make a quick return of all of these folding members, the spring 151, is shown attached to the arm 150, so that as soon as the acting portion of the double cam 153, passes the rollers 146—146, said parts are all drawn down quickly by said spring 151, to their normal positions, with the folding members open to give clearance for the next partial revolution of the wheel structure 6. I will now describe the mechanism by means of which the folding packages are discharged from the down pocket, that is, the pocket occupying the position of pocket 6^e, in Fig. 5. Referring to Figs. 1, 3 and 7, there is mounted on the base 1, of the machine, a box-like slide casing 178, within which is a sliding plunger 179, also of box-like construction, having its top middle portion open lengthwise thereof, and provided in its bottom with a longitudinally extending rack 180. Mounted between the upright frame members 2 and 3, Fig. 3, is a shaft 130

181, provided in its middle portion with a gear 182, adapted to be engaged by a segment 183, formed upon the lower end of a pendulum-like lever 184, pivoted at its upper end on the shaft 16, said lever 184, having a longitudinally extending roller slot 185, within which works a roller 186, on a disk 187, which disk is mounted upon the outer end of a shaft 188, secured at its inner 10 end to the upright frame member 3, and provided with a spacing sleeve 189.

Also mounted on said shaft 188, at the end of said sleeve, is a gear 190, which is secured to, or is made as a part of, said disk 187, 15 and is in position to mesh with and be driven by the large gear 19, mounted on the shaft 16, whereby as said segment-lever 184, is oscillated by the turning of said disk 187, it operates through the gear 182, to turn the shaft 181. Mounted on the inner end of the shaft 181, is a beveled gear 191, adapted to mesh with a beveled gear 192, on a shaft 193, provided at its opposite end with a gear 194, which meshes with and operates 20 the rack 180, in the sliding plunger 179, said sliding plunger being adapted to be moved through the down pocket, occupying the position of the pocket 6^a, in Fig. 5, whereby said plunger forces the wrapped package 25 out at the opposite side of said pocket into the open end of a box-like receptacle 195, pivotally mounted, as at 196, Fig. 7, and provided with a handle 197, whereby it can be tipped to the position shown in dotted 30 lines, Fig. 7, to discharge the wrapped package 35 therefrom.

Mounted in the base, directly below the down pocket, that is, pocket 6^a, Fig. 5, is a platform-like member 198, yieldingly supported on springs 199, which operate to compress the packages as they come to this position, and before they are discharged from the machine.

The use and operation of my invention 45 may be briefly described as follows:

The raisins are fed through the finger members 42—42, in the feeding mechanism, for the purpose of breaking them up before they are delivered to the feed belt 46, by 50 means of which they are carried to the weighing receptacle 55. When a sufficient quantity of raisins has been discharged into the receptacle 55, to overbalance the weight 63, said receptacle descends with its weight, 55 the holding finger 59, slipping from under the weighted arm 60. As said receptacle descends, the cam finger 71, which operates the rocker lever 70, on the side of said receptacle, engages with the cam block 72, and 60 is operated for opening the bottom members 68—68, of said receptacle, for automatically discharging the raisins from said receptacle. In the meantime the end of the wrapping paper has been fed forwardly 65 underneath the receptacle and above the

opening 10, through the casing 9, which contains the wheel structure having the wrapping pockets therein. As the matter is discharged from said receptacle it sinks with the wrapping paper into the uppermost 70 pocket, which would be 6^a, Fig. 5, assuming the form shown in Fig. 11. The knife 113, in the meantime has been operated for cutting off the quantity of wrapping paper required for the package. At this point the 75 machine is automatically thrown into gear, in the manner described, by the tripping of the clutch lever 38. The folding members 132 and 133, are automatically operated in the order mentioned by the mechanism, hereinbefore described, folding the paper over the matter into the form shown in Fig. 12. The wheel structure 6, rotates an eighth of a turn, bringing the pocket 6^a, into the position occupied by the pocket 6^b, Fig. 5, whereupon the folding members 136—136, at opposite sides of the wheel structure are operated to fold the bottom ends of the package into the form shown in Fig. 13. The package in pocket 6^a, is also being operated 90 upon as is the package in the pocket 6^b. The package in the pocket 6^a, is having the sides of the ends of the wrapper folded into the position shown in Fig. 14, while the package in the pocket 6^b, is having the tops of the 95 ends folded into the position shown in Fig. 15. The package in the pocket 6^a, is being automatically discharged from the pocket. Thus all of the packages in the pockets 6^a, 6^b, 6^c, 6^d and 6^e, are being operated 100 upon simultaneously. A completely wrapped package is ejected from each pocket as it comes to the position occupied by pocket 6^a, Fig. 5.

It will be seen, therefore, that the machine automatically separates the raisins, feeds them to the weighing mechanism, discharges them on to wrapping paper which is automatically fed into place to receive the same, and automatically wraps the raisins 110 into a compact uniform package and discharges it ready for the box or carton into which it is placed for the market.

I am aware that many changes can be made in the mechanisms here shown and described for performing the various functions of my invention, without departing from the spirit thereof, and I do not, therefore, limit the invention to the mechanical details here shown, except as I may be limited by the hereto appended claims.

I claim:

1. In combination, a weighing receptacle to receive matter to be wrapped, means normally holding said receptacle in a loading 125 position, said means being adapted to yield when a predetermined amount of matter has been put into said receptacle, means adapted to be automatically operated by the movement of said receptacle when loaded for dis- 130

- charging its load, wrapping mechanism positioned to receive the discharged load and adapted to automatically wrap said matter, and interconnections between said weighing mechanism and said wrapping mechanism, whereby the movement of the weighing receptacle and the discharge of its load automatically sets in operation the wrapping mechanism, substantially as described.
- 5 10 2. In a machine of the character referred to, in combination, a movable receptacle to receive matter to be wrapped, means normally holding said receptacle in loading position, said means being adapted to yield 15 when a predetermined amount of matter has been put into said receptacle, means adapted to be automatically operated by the downward movement of said receptacle and its contents for discharging the latter, 20 means for automatically returning the receptacle to loading position, wrapping mechanism adapted to receive and automatically wrap the discharged matter, whereby to remove it from the discharging position, and 25 operating connections between said receiving and discharging mechanism and said wrapping mechanism, whereby the latter is caused to operate by the discharge operation of the receiving and discharging mechanism, 30 substantially as described.
3. In a machine of the character referred to, an automatic wrapping mechanism comprising a cylindrical casing, a wheel structure revolvably mounted therein and provided 35 around its outer face with a series of wrapping pockets, open at their ends and outer sides, folding members arranged in pairs and hingedly secured in said casing, one pair being adapted to fold wrapping paper over 40 the top of said package, another pair being adapted to fold the bottom end portions of the package, another pair being adapted to fold the side end portions, and another pair being adapted to fold the top end portions, 45 said pairs of folding members being distributed around said casing so that each pair registers with a pocket in said wheel structure, a plunger mounted in register with one of said pockets with means for operating the 50 same through said pocket for ejecting the wrapped package therefrom, and operating connections for simultaneously operating said several folding members and said plunger, substantially as shown and described.
- 55 4. In a machine of the character referred to, in combination with a wrapping pocket adapted to receive a quantity of wrapping paper and the matter to be wrapped, folding wings hingedly mounted above said wrapping pocket and normally inclined backwardly from said pocket, whereby to permit matter to be freely discharged into said pocket, a container to receive the matter to be wrapped, said container being adapted 60 to move downwardly between said folding members into close proximity to said wrapping pocket, means for automatically and alternately operating said folding members, whereby to fold the paper over the top of said matter in said wrapping pocket, substantially as described.
- 65 5. In a machine of the character referred to, in combination, a revoluble wheel structure provided in its outer face with a series of wrapping pockets, means for automatically and intermittently revolving said wheel structure, means for automatically feeding a quantity of wrapping paper and matter to be wrapped into said wrapping pockets, folding members pivotally disposed in pairs adjacent said wrapping pockets and at opposite sides thereof with means for automatically and simultaneously operating the same, whereby to fold the wrapping paper about said matter as said wheel 70 structure is moved forwardly, step by step, and a compressing member, into register with which said wrapping pockets are successively moved, automatically operated for compressing said package preceding its discharge from the said wrapping pocket, substantially as described.
- 75 6. In a machine of the character referred to, in combination, a supporting structure, a wheel structure revolvably mounted therein and provided with a series of wrapping pockets, means for automatically feeding a quantity of paper and matter to be wrapped into said pockets, folding members pivotally mounted in pairs on said supporting structure adjacent said wrapping pockets, some of said folding members being adapted to be independently moved bodily into operative positions opposite said pockets, with means for so moving the same, and other means for 80 automatically and simultaneously operating said folding members upon their pivots for automatically folding said wrapping paper about the matter in said pockets, substantially as described.
- 85 7. In a machine of the character referred to, in combination with a wrapping pocket adapted to receive the matter to be wrapped, folding members pivotally and slidably mounted adjacent said wrapping pocket, means for automatically moving said folding members into positions opposite said wrapping pocket, and means for automatically turning said folding members upon their pivotal mountings for automatically 90 folding wrapping paper about matter to be wrapped within said pocket, substantially as described.
- 95 8. In combination, a receptacle to receive matter to be wrapped, balancing mechanism controlling the movement of said receptacle and its contents, discharging mechanism adapted to be automatically actuated by 100
- 105 110 115 120 125

- the downward movement of said receptacle and its load, wrapping mechanism positioned thereunder to receive the discharged matter, and comprising a revolving structure having wrapping pockets adapted to be moved successively under the said receptacle, operating means for said wrapping mechanism controlled by the downward and discharging action of said receptacle and adapted to be automatically set into action thereby, and coöperating means for automatically feeding wrapping paper to said wrapping mechanism.
9. In combination, a receptacle to receive matter to be wrapped, balancing mechanism for supporting said receptacle and a predetermined amount of matter therein, means for discharging matter from said receptacle automatically when a predetermined amount thereof has been placed therein, wrapping mechanism for receiving and wrapping said matter comprising a structure provided with receiving pockets, means for moving the same to bring said pockets successively into position to receive matter from said receptacle, means for feeding wrapping paper to said pockets, hinged folding members arranged in pairs at opposite sides of said pockets, means for automatically and successively operating said folding members to fold said paper about said matter in said pockets, and means for discharging the wrapped package from said machine, and inter-dependent controlling means between said balanced receptacle and said wrapping mechanism, whereby the action of the former sets in action the latter, and means for discharging the wrapped matter from said machine.
10. In combination, a receptacle adapted to receive a quantity of matter to be wrapped, a balancing mechanism supporting said receptacle and adapted to yield when a predetermined amount of matter has been put into said receptacle, closure members for said receptacle adapted to be moved to discharge the contents of said receptacle, means for moving said closure members to open position as said receptacle and its contents moves downwardly, wrapping mechanism under said receptacle comprising a structure provided with receiving pockets adapted to be moved successively into position to receive discharged matter direct from said receptacle, means for feeding wrapping paper to said pockets prior to the discharge of matter thereinto, folding members hingedly positioned in pairs at opposite sides of said pockets for folding said paper about said matter therein, means for operating said folding members, inter-dependent controlling means between said balanced receptacle and said wrapping mechanism, whereby the action of the former sets in action the latter, and means for discharging the wrapped matter from said machine.

Signed at Portland, Multnomah county, Oregon, this 6th day of September, 1916.

GOTTHOLD L. LANGER.

In presence of—

I. M. GRIFFIN,
J. C. STRENG.
